UNITED STATES PATENT OFFICE.

HERMANN KURZ, OF NEWARK, NEW JERSEY, ASSIGNOR OF ONE-HALF TO WILLIAM J. BAUER, JR., OF NEWARK, NEW JERSEY.

SAFETY ATTACHMENT FOR ELEVATORS.

1,173,722.

Specification of Letters Patent. Patented Feb. 29, 1916.

Application filed July 3, 1914. Serial No. 848,722.

To all whom it may concern:

Be it known that I, HERMANN KURZ, a citizen of the United States, residing at Newark, in the county of Essex and State 5 of New Jersey, have invented certain new and useful Improvements in Safety Attachments for Elevators; and I do hereby declare the following to be a full, clear, and exact description of the invention, such as 10 will enable others skilled in the art to which it appertains to make and use the same, reference being had to the accompanying drawings, and to characters of reference marked thereon, which form a part of this 15 specification.

This invention relates, generally, to safety appliances for elevators; and, the present invention has reference, more particularly, to a novel safety-attachment in 20 the form of pivoted clutch-arms or bars which, upon the breaking of the cage-carrying cable will automatically, by gravity, be brought into frictional holding engagement with the guide or side-rail upon the 25 dropping of the cage, whereby serious accidents and loss of life are prevented.

The present invention has for its principal object to provide a novel and simple, as well as an efficiently operating safety- 30 attachment for elevators, the clutch-arms or bars of which, upon the breaking of the cable, are adapted to grip the elevator side-rails with a gradual resisting effect, so as to prevent any sudden stoppage and extreme jarring of the elevator car or cage, the gripping portions of the clutch-arms or bars being provided with resilient gripping elements which, upon engaging the side-rails aid in throwing the clutch-arms 35 to their complete operative position in gripping contact with said side-rails, whereby the dropping car is brought to a stop.

Other objects of the present invention not at this time more particularly enumerated will be clearly understood from the 45 following detailed description of the invention.

With the various objects of the invention in view, the said invention consists, 50 primarily, in the novel safety-attachment for elevators hereinafter set forth; and, the invention consists, furthermore, in the novel arrangements and combinations of the several devices and parts, as well as in the

details of the construction of the said 55 parts, all of which will be more fully described in the following specification, and then finally embodied in the clauses of the claims which are appended to and which form an essential part of the said specification. 60

The invention is clearly illustrated in the accompanying drawings, in which:—

Figure 1 is an elevation of a fragmentary portion of an elevator-car or cage and the 65 side-rails, with a safety-attachment, showing one embodiment of the principles of the present invention, mounted upon the body of the car or cage, the clutch-arms or bars of the safety-attachment being shown 70 in their normal position out of gripping engagement with the side-rails, when the car or cage is suspended by means of an unbroken cable; and Fig. 2 is a similar view of the same devices and parts, showing the 75 clutch-arms or bars in their retained and gripped relation with the side-rails when the cable is broken. Fig. 3 is a detail transverse vertical section, taken on line 80 3—3 in said Fig. 2, looking in the direction of the arrow *x*; and Fig. 4 is a top or plan view of the devices and parts represented in said Fig. 1, with the side-rails shown in cross-section.

Similar characters of reference are employed in the above described views, to indicate corresponding parts. 85

Referring now to the several figures of the drawings, the reference-character 1 indicates the fragmentary portion of any 90 suitably constructed elevator-car or cage, and 2 indicates the usual cable.

The reference-characters 3 indicate the side-rails between which the car or cage moves up and down, said rails being suitably secured in proper positions to the side walls of the elevator-well, or to the usual steel frame-structure sometimes employed. 95

Suitably secured upon the roof of the car or cage 1, usually by means of bolts 4, or 100 other suitable fastening devices, are suitably constructed uprights or standards, as 5, these standards being arranged, usually, in pairs so as to provide spaces 6 between them, and suitably secured upon the upper end-portions of said uprights or standards 5, by means of bolts 7 and angle-irons 8, or other 105 suitable fastening means, is a suitably con-

structed cross-bar or tie-plate 9. This cross-bar or tie-plate 9, at its middle, is preferably made with a hub 10 which is formed with an opening 11, into and through which the cable 2 extends, substantially as shown in Figs. 1, 2 and 3 of the drawings. Suitably connected with each pair of the said uprights or standards 5 are suitable pivot-bolts, as 12, which extend across the said spaces 6 between the said pairs of uprights or standards 5. Fulcrumed upon said pivot-bolts 12, by means of elongated slots or holes, as 13, are a pair of clutch-bars or arms 14, in such a manner, that the arm-portion 15 of each bar is shorter than its arm-section 16, as clearly shown in Figs. 1 and 2 of the drawings. The free end-sections 17 of the arm-sections 16 are preferably made in enlarged form so as to provide additional weight, and the purposes of which enlarged portions 17 will be self-evident. As shown in the several figures of the drawings, the said enlarged portions 17 of the respective clutch-bars or bars 14 are arranged side by side, and are pivotally connected by means of a bolt 18, the said bolt also carrying a suitable clevis, as 19, or other suitable means of suspension, to which the end of the cable 2 is suitably attached. In order to properly guide the car or cage 1 during its up and down movements, and also to keep the clutch-bars or bars 14 in proper alignment with the side-rails 3, the end-sections of said clutch-bars or bars are suitably forked, as at 20, and in the crotch of said forked portions, are suitably gripping or binding members or elements, as 21, which are made of a suitable material having resilient properties, such as rubber or the like.

The manner of securely suspending the elevator-car or cage, and the manner of normally retaining the clutch-bars or bars by means of the cable in their angular relation to each other, and so that the gripping or binding elements 21 are kept from engagement with the side-rails 3, as long as the cable 2 remains unbroken is clearly represented in Fig. 1 of the drawing; and the manner of bringing the gripping or binding elements 21 into frictional retaining engagement with the side-rails is clearly shown in Fig. 2 of the drawings, and need, therefore, not be further described.

With the use of the resilient gripping or binding elements 21 it will be evident, that in case of a break in the cable, these elements will permit of a gradual retarding action between the elements and the side-rails 3, so that the car or cage 1 will not be stopped too suddenly, thus preventing sudden jarring and serious shocks to any person or persons in the said car or cage, and, furthermore, they provide by the checking or resistance they offer to travel on the side-

rails a means which aids in completely throwing the clutch-bars 14 to operative positions.

If desired, and as illustrated in Figs. 1 and 2 of the drawings, the side-rails 3 may be provided with suitably formed recesses, as 22, at suitable intervals in the rails, said recesses being formed with stops, as 23, with which the lower portions 24 of the spread clutch-bars or bars 14 are adapted, at the proper time, to be brought into arrested and supporting engagement.

Of course I am fully aware that changes may be made in the general arrangements and combinations of the various devices and parts, as well as in the details of the construction of the said parts as set forth in the foregoing specification and as defined in the clauses of the claims without departing from the scope of my present invention. Hence, I do not limit my present invention to the exact arrangements and combinations of the several devices and parts as described in the said specification, nor do I confine myself to the exact details of the construction of the said parts as illustrated in the accompanying drawings.

I claim:

1. In a safety-appliance for elevators, in combination with an elevator-car, standards mounted upon said car, and a tie-plate secured to and connecting the standards, pivot-bolts connected with said standards, clutch-bars having elongated slots for fulcruming said clutch-bars upon said pivot-bolts, a pivot-bolt for pivotally connecting the inner end-sections of the said clutch-bars, a means of suspension connected with said last-mentioned pivot-bolt, side-rails having stop-notches therein with which the outer ends of said clutch-bars will engage, and a resilient gripping element connected with the side-rail engaging end-portion of each clutch-arm adapted by frictional resistance when engaged with said side-rails to throw said clutch-bars in engaging position relative to said stop-notches.

2. In a safety-appliance for elevators, in combination with an elevator-car, of a supporting cable, standards mounted in pairs near each side of the car, and a tie-plate mounted upon and secured to the pairs of standards, said tie-plate being formed with a tubular hub for the passage therethrough of a cable, pivot-bolts connected with each pair of standards, clutch-bars having elongated slots for slidably fulcruming said clutch-bars upon said pivot-bolts and between the standards, a pivot-bolt for pivotally connecting the inner end portions of said clutch-bars, a means of suspension connected with said last-mentioned pivot-bolt to which said cable is attached, side-rails having stop-notches therein with which the outer ends of said clutch-bars

will engage, and a resilient gripping element connected with the side-rail engaging end-portion of each clutch-arm adapted by frictional resistance when engaged with said 5 side-rails to throw said clutch-arms in engaging position relative to said stop-notches.

Copies of this patent may be obtained for five cents each, by addressing the "Commissioner of Patents, Washington, D. C."

In testimony, that I claim the invention set forth above I have hereunto set my hand this 30th day of June, 1914.

HERMANN KURZ.
